UNITED STATES PATENT OFFICE

2,481,634

SULFURIC ACID CHAMBER

Edward A. Werner, Atlanta, Ga.

Application March 8, 1946, Serial No. 653,099

1 Claim. (Cl. 23—284)

1
This invention relates to improvements in acid chambers of the general type disclosed in U. S. Patents 1,112,546 and 1,627,043 and identified in the art as the Mills-Packard type of sulphuric acid chamber.

Chambers of this type comprise a bottom "pan" composed of lead and in which the acid collects, and a lead chamber or casing suspended in a suitable framework above the pan. In some instances the lower edge of the side wall or "curtain" of the chamber is burned to the upper edge of the side wall or upstand of the pan; and in other cases the chamber is supported with the lower part of the curtain encircled by and spaced from the said upstand and with the lower edge of the curtain below the plane of the upper edge of the upstand and elevated above the bottom of the pan. In the latter case the acid in the pan forms a liquid seal at the bottom of the chamber. In either case it is customary to provide an external support and reinforcing, backing, for the said upstand. Conventionally, the said casing or lead chamber is suspended in a framework which embraces both the pan and the casing as herein-after more specifically set forth.

The present invention has for its primary object the provision of an improved means for supporting and reinforcing the upstanding wall of the said pan, said supporting means being of a character to afford ready access when necessary to the outer face of said wall for inspection and repair, and particularly to afford access to the critical area at the juncture of the upstanding side wall of the pan and the bottom wall, within which area the pan is most subject to deterioration.

More specifically the invention contemplates a novel supporting structure for the pan upstand composed of a number of sections individually readily detachable so as to uncover the adjoining portion of the pan wall.

The invention further resides in certain novel structural arrangements and details hereinafter described and illustrated in the attached drawings wherein:

Fig. 1 is a fragmentary elevational and partial sectional view showing the lower portion of a chamber made in accordance with the invention;

Fig. 2 is an enlarged fragmentary vertical sectional view showing more clearly the details of the illustrated embodiment of the invention;

Fig. 3 is a section on the line 3—3, Fig. 2;

Fig. 4 is a section on the line 4—4, Fig. 2, and

Fig. 5 is a view in perspective of one of the elements of the structure.

With reference to the drawings, the pan pre-

viously described is indicated by the reference numeral 1, this pan resting in the present instance upon a suitable concrete or other foundation 2. The campanulate casing is indicated at 3, and the embracing framework which in the present instance supports the casing 3 is indicated generally by the reference numeral 4. In general this framework comprises an annular series of relatively spaced upright structural members 5 and transverse members 6 which extend between and unite said uprights. The lead curtain 7 of the casing has secured to the outer face thereof a series of upwardly extending bars 8, and links 9 are attached to these bars and to the cross bars 6 of the framework and function to suspend the casing in the frame with the lower end thereof centrally disposed within the pan 1 and with the lower edge 11 of the casing elevated above the bottom of the said pan. The structure as described above is conventional and forms no part of my invention, except as to certain details described below.

The frame members 5 are, in the present instance, T-shaped in cross section, as best illustrated in Fig. 4, and the lower ends of these sections seat upon and are secured to foot plates 12 which rest upon and are secured to the foundation 2 by means of bolts 13. The wall or upstand 14 of the pan 1 rests flatly against the surfaces 15 of the heads 16 of the respective frame members 5. In accordance with the invention the said wall 14 is reinforced or backed in the areas intermediate the said members 5 by plates 17 of segmental form, best shown in Fig. 5, one of which extends between each adjoining pair of said upright frame members. The plates 17 conform substantially in height to the wall 14 and have at each end an outwardly off-set flange 18 which in assembly overlies the respective side portions of the head 16 of the frame member as best illustrated in Fig. 4. The flanges 18 are apertured at 19 for reception of studs 21 which are secured in and project from the said head portion 16 of the frame member whereby through the medium of associated nuts 22 the said plates may be secured against the outer faces of the said head 16. By reason of the fact that the flanges 18 are off-set forwardly from the body of the plate 17 to the required extent, the inner faces 23 of the plates 17 are in effect flush with the faces 15 of the frame members 5 and form with the latter a substantially continuous backing surface for the wall 14. Each of the plates 17 is provided at the top with an outwardly projecting flange 24 and at the bottom with a reinforcing channel 25, the lower

flange 26 of this channel seating upon the foundation 2. As best shown in Fig. 2, the wall 14 extends outwardly over the top of the flange 24 and is secured to the latter by means of bolts 27.

In accordance with the conventional practice in the operation of chambers of this character in the production of sulphuric acid, means is provided, not illustrated, for flowing water downwardly over the curtain of the casing 3. Adjacent to the bottom of the curtain and to the top of the pan 1, a trough 31 is provided which is secured to the outer face of the casing and extends completely around the latter. The trough is provided at one or more points in the bottom thereof with discharge ducts 32 through which the water may be conducted outwardly beyond the confines of the pan 1, see Fig. 1. Also in accordance with conventional practice the pan 1 is provided in its bottom with one or more discharge openings 33 which is normally closed by a suitable stopper 34 at the lower end of a stopper-manipulating rod 35, said rod extending upwardly to the top of the wall 14 so that it may be available for removal or reinsertion of the stopper 34 as may be required.

It will be apparent that whereas the afore-described construction affords a continuous backing for the wall 14, and an adequate support for said wall, the detachability of the individual plate elements 17 provides a ready means for access to the outer surface of the wall for inspection and repair. It is to be noted also that since the plates 17 extend completely to the bottom of the wall 14 that removal of the plates will afford access to the area at the juncture of this wall with the bottom of the pan where deterioration of the pan structure is most apt to occur.

Attention is directed to the links 9 and the manner in which they are secured in the structure, as illustrated in Figs. 2 and 3. It will be noted that the threaded upper ends 36 of the links pass through apertures in the transverse members 6 and in the brackets 37 of the uprights 5 upon which the members 6 are supported. The said link ends 36 also pass through apertures in anchor plates 38 which, in the present instance, are welded to the member 6, and which are disposed at an angle to the horizontal such that the plane of the plate is normal to the longitudinal center line of the link 9 when the latter

has assumed a normal position in the assembly as shown in Fig. 2. The plates 38 thus form normal seats for the retaining nuts 39 on the upper ends of the links and the latter are stressed in alignment with their longitudinal axes.

While the invention has been described and illustrated in connection with the "open" or liquid-sealed form of chamber, it is apparent that it is applicable also to the "closed" form of chamber, wherein, as set forth, the lower end of the curtain is joined to the upstand of the pan.

I claim:

In a sulphuric acid chamber, a pan having an upright side wall, a supporting framework, a lead chamber supported by said framework with the bottom edge thereof within said pan and elevated from the bottom of the latter but below the upper edge of the side wall, said framework comprising an annular series of uprights of T-section embracing said pan and arranged with the head portions of the T's confronting the upright side wall of the pan and forming flat abutments for the outer face of said wall, and a plate section spanning the space between each adjoining pair 25 of said uprights with the side edges thereof contiguously to the side edges of the said head portions of the uprights so as to provide a continuous flat backing for the said outer face of the wall, said plate sections having at the sides 30 thereof offset flanges overlying the outer faces of said head portions and detachably secured to the uprights.

EDWARD A. WERNER.
